REMOTE CONTROL SYSTEM

Herbert Spencer Polin, New York, N. Y., assignor
to Polin, Inc., New York, N. Y., a corporation
of Delaware

Application April 9, 1932, Serial No. 604,228

21 Claims. (Cl. 175—320)

The present invention relates broadly to control apparatus for effecting a desired operation or sequence of operations in response to electrical impulses. More particularly the invention pertains to control apparatus of this character responsive to electrical impulses transmitted from a remote point.

This application is a continuation in part of my copending application Serial No. 578,608, filed

10 December 2, 1931.

The control apparatus of the present invention distinguishes fundamentally from others of the class defined in its ability to respond to sudden electrical changes of extremely short duration. Employed for purposes of remote control the system obtains discrimination in this fashion without the necessity for selecting circuits, by utilization of control impulses which, although of large amplitude, are of such short duration and 20 small energy content as to be without effect upon all but the most delicate electrical appliances.

The invention therefore provides a means of utilizing an electrical power supply line, such as a residence lighting system, while operating in 25 its normal manner, as the impulse conducting medium for remote control operation. Applied in this fashion the energy of the power line may be utilized to generate the remote control impulses as well as to actuate the controlled apparatus in response thereto.

During such joint use of the power line conductors, the functions of power supply and remote control are effected in mutual independence. The normal variations in line voltage due to 35 random fluctuations of the power load are insufficient to affect the control apparatus. On the other hand the remote control impulses are of such small energy content and transient character as to produce no observable effects upon 40 or injury to the power equipment.

The advantages of a remote control system possessing such features are at once apparent. Inasmuch as outlets from a residence lighting system are already available in all parts of a building, the obstacle of providing the requisite conductors for transmitting the control impulses is at once obviated. Flexibility is present in extreme degree in that the sending and controlled 50 units may be plugged into any of the lighting outlet sockets for operation between any two points of the building. The entire control equipment may be completely disconnected from the lighting system with equal facility. That is, the 55 entire apparatus may be of a portable character

utilized for the most temporary expedient in providing remote control actuation.

The possible uses of a control system having these characteristics appear almost unlimited. In the home the apparatus may be employed 5 remotely to switch a fan or the like on or off, to tune a radio set, or to regulate a furnace. In connection with the latter objective, regulation may be effected automatically by employing an electric clock or a thermostat to control the 10 transmission of impulses.

The control system of the present invention when installed in one residence, or apartment will function independently of similar apparatus installed in other residences in the vicinity, 15 or other apartments in the same building. This results from the fact that the meter installed by the power companies at the inlet from the feeder line to each residence or apartment, serves effectually to prevent control impulses applied to 20 the lighting system in one residence or apartment from affecting similar apparatus located in another residence or apartment. The basis of this expedient may be applied generally to arbitrarily section off a line for remote control purposes by 25 insertion of small inductances between line sections it is thus desired to isolate.

The invention is not restricted in its use to remote control between parts of a building, or even to the use of wires as a conducting medium for 30 the control impulses. These may be transmitted by wireless waves in which event the controlled portion would be associated with suitable radio receiving equipment.

Aside from the field of remote control the 35 invention is generally applicable for effecting mechanical operations in response to transient electrical current surges of short circuit magnitude operative over extremely small time intervals. A suggested use of this character is that 40 of lightning protection for power lines and the like. Current surges upon a line due to lightning discharge, although destructive in effect, are of such extremely brief duration that difficulty is experienced in providing protective apparatus 45 which responds with sufficient rapidity. The present invention appears ideally adapted to such use.

The controlled or actuating portion of the system comprises in one modification an electronic 50 space discharge device, such as a thermionic tube, employed as a diode by connecting its cathode with one side of the power supply system, a connection extending from the anode of the tube through an actuating element, such as a relay, 55

to the other side of the power system. Usually it is found desirable to connect a condenser in shunt to the relay winding. The cathode may be heated from a local source, but preferably is energized directly from the supply system, as by connection of the filament in series with suitable resistance between conductors of the system. If the tube utilized is provided with a control grid this may be left free of electrical connection or "floating".

10 The actuating mechanism employs in a second modification a thermionic tube having at least a control grid in addition to its anode and cathode. The cathode and anode, as before, are suitably connected with opposite sides of the power system, the latter through the relay winding or other actuating element employed. The control grid may be connected between a pair of identical impedances serially connected between the conductors of the power line, each impedance preferably consisting of a resistance in series with a condenser.

15 The impulse transmitting mechanism in its simplest form comprises nothing more than a fixed condenser of suitable capacity value, associated with suitable switching means for connecting the condenser across the power line. Especially on direct current systems the switch should be such as to reverse the condenser terminals for successive connections, this to assure 20 discharge and charge of the condenser for each connection, inasmuch as proper functioning of the control apparatus is dependent upon the short circuiting effect of this condenser.

25 30 35 Having now generally described the invention, reference will be had to the drawing for a more detailed description of the circuits employed and an explanation of the observed phenomena.

40 45 In the drawing, Figs. 1 and 2 show modifications of the invention adapted for use in remote control on residence lighting and power supply systems.

Fig. 3 shows the actuating mechanism employed as a lightning protective device for electrical power and distribution systems.

50 Referring to Fig. 1, conductors F represent a feeder line extending from an electric light and power generating plant supplying electrical energy to consumers at a line voltage E. Tapped off from the feeder at various points are a number of branch lines 1-3 inc. each extending through a meter M to the office, residence, apartment, etc., of an individual consumer.

55 60 65 A remote control system in accordance with the present invention is associated with branch line 3 on the side of the meter opposite to that of the feeder F. The controlled or actuating device comprises a space discharge device or thermionic tube V, here shown as of the three-element type, having its cathode K connected at one terminal to one side of the line 3, the opposite terminal of the cathode extending through variable resistance 4, to the opposite side of the line for providing the heating current. From the anode P 70 75 a connection extends through an actuating element R, such as a telephone switching relay, and a variable resistance r₃ to the upper conductor of the power line. Connected in shunt to the relay winding is a fixed condenser C₁. The control grid G is shown unidentified with any portion of the system and is thus said to be "floating".

The impulse sending device comprises fixed condenser C₂ the terminals of which extend to a switch S for connecting the condenser across line 75 80 85 90 95 100 105 110 115 120 125 130 135 140 145 150 The switch may be of a manually operated type. The drawing shows a rotary switch, adapted to be driven by any suitable means, manually or by a motor, brushes 5 and 6 of which connect to the condenser terminals. The brushes contact 5 with slip rings 7 and 8 to which rotary contacts 9 and 10 are connected. Upon rotation of the switch, rotary contacts 9 and 10 contact with stationary contacts 11 and 12 connected to the respective sides of line 3. As a result of this 10 arrangement it will be apparent that continued rotation of the switch reverses the connection of the condenser terminals for successive contacts.

The observed operation of the control system is that connecting the fixed condenser C₂ between conductors at any point of the lighting system causes the relay R of the actuating circuit, wherever located, to release and then re-operate after a brief interval. If the switch is operated intermittently at a rate not less than 20 say several times a second, for the particular apparatus utilized, causing the fixed condenser C₂ to be thus periodically connected across the line, relay R of the actuating circuit will release and remain continuously released until the intermittent switching ceases, when after a pause the relay will re-operate.

Consider now that condenser C₂ is fully discharged and that switch S is advanced until rotary contacts 9 and 10 make contact with stationary contacts 11 and 12 respectively, thereby connecting the condenser C₂ across the line. At 50 the instant of connection, condenser C₂ acts as a momentary short circuit on the line, instantly reducing the line voltage E₁ across the relay circuit momentarily to zero. As condenser C₂ thereafter charges up, the voltage E₁ across the tube and relay circuit rises in substantial correspondence with the voltage at the condenser terminals, ultimately resuming its normal value of E when the condenser C₂ is fully charged.

The sudden drop and more gradual rise of the line voltage E_1 produces a corresponding variation in the flow of space current through tube V, due to the fact that the relay circuit is rendered almost reactionless by proper selection of the capacity value C_1 in shunt to the relay winding. The drop in space current causes the relay current to decrease below its release value, the period of decay being expedited to this end by the accumulated charge on condenser C_1 equal to the normal voltage drop across the relay winding.

The building up of the relay current to its normal value is more gradual than the building up of the line voltage E_1 due to the presence of condenser C_1 , which, practically discharging during the decay period, substantially short circuits the relay winding upon resumption of current flow in the space path of the tube. It is not until the condenser C_1 becomes charged to an appreciable potential that any considerable current again flows through the relay winding. This condenser charge accumulates slowly at first due to the excessively high space path resistance of the tube at low anode potentials. Inasmuch as the operating current of the relay is considerably higher than its release value, the period of re-operation is delayed to this extent by the additional time required for the current to attain this higher operating value.

In view of the fact that the control grid G of tube V is maintained free of electrical connection, i. e. "floating", any negative charge accumulating thereon will of course affect the operation of the relay circuit. It has been experimentally observed that a grid left free or "floating" obtains a negative potential, increasing in magnitude, as the anode potential of the tube is reduced to zero. This results from the fact that low values of anode potential are insufficient to draw all of the electrons past the grid, so that a number find lodgment there to establish a negative biasing potential on the grid. This, of course, reduces the magnitude of space current for a given positive potential applied to the anode.

This effect has been observed to influence noticeably the operation of the system of Fig. 1, upon continued rotation of switch S for an appreciable time interval at such speeds as to maintain low average potential between cathode and anode of tube V. Upon stopping the switch it has been observed that the relay does not re-operate for a matter of 10 to 15 seconds thereafter for the particular apparatus employed. This represents the time required for the grid charge to leak off to the anode following resumption of the normal line potential E . That the effect noted is due to an accumulated negative charge on the grid is demonstrated by the fact that grounding the grid, as by touching it, produces immediate reoperation of the relay.

This same action occurs although in less degree even for an isolated connection of condenser C_2 . Prior to such connection a cloud of electrons is being impelled from the anode past the grid at a definite average velocity determined by the normal anode potential. Bridging condenser C_2 removes the impelling force almost instantaneously, thereby permitting a number of electrons to find lodgment upon the grid to establish there a negative potential which leaks off slowly upon resumption of the normal line voltage.

It will be observed that the several factors recited, act cumulatively to reduce the relay current rapidly below its release value and to retard its subsequent building up to its much higher

operating value. As a consequence the almost instantaneous short circuiting effect due to connecting condenser C_2 is magnified into an interval of considerable duration during which the relay current is maintained below its release and reoperate values, such intervals proving ample for the relay mechanically to effect release followed by reoperation for each isolated bridging of the condenser.

The system of the present invention is thus enabled to detect instantaneous changes in line voltage by its instantaneous electrical response to such changes followed by an automatic delay in returning to normal, sufficient to enable the actuating element, i. e. relay R, mechanically to respond to the change.

By proper proportioning of the inductance and capacity in the relay circuit R— C_1 , satisfactory operation will be obtained upon replacing the three-electrode tube V employing the "floating" grid with a true diode or two-element tube having only a cathode and an anode connected as shown.

In view of the foregoing it is now apparent why continued rotation of switch S above a certain critical speed maintains relay R in its released condition. The line is capacitively short circuited by condenser C_2 with such rapidity that the relay current does not have opportunity to build up to its operating value between successive connections of condenser C_2 .

Thus far the explanation has been restricted to operation of the system upon direct current lines. It has been observed to function equally well for alternating current supply. Assuming the line voltage E, Fig. 1, to be the usual 60-cycle alternating current supply, the resultant space current flowing through tube V will comprise a succession of uni-directional pulses corresponding to the alternate half-waves of the impressed line voltage E. The relay current, however, does not pulsate between zero and a maximum value in the same fashion as the space current, owing to condenser C_1 discharging into the relay winding during intervals when the line voltage renders the tube anode negative relative to its cathode. As a result of this action the relay current comprises a steady component, of magnitude sufficient to maintain the relay operated, together with a superimposed ripple current.

The action of the current in the relay winding in carrying over from peak to peak of the impressed alternating voltage in this fashion, is based upon entirely different considerations from its reduction below the release value due to bridging condenser C_2 . In the one instance we are dealing with a so-called "steady state" condition due to a cyclically varying applied potential, whereas in the other instance we are dealing with a purely transient phenomena caused by shock excitation of the system. In the case of the alternating current supply, the rectified voltage applied to the relay circuit R— C_1 is analyzable into a steady component with a superimposed 60-cycle alternating voltage. This is clearly a steady state condition to which the circuit R— C_1 presents a true alternating current impedance, and one which does not introduce the transient action ascribed to condenser C_2 .

Upon establishment of steady state conditions, the alternating current potential does not permit a negative biasing voltage to be established on the control grid, inasmuch as electrons impinging thereon are impelled by the applied voltage to leak off continuously either to the cathode or the anode, whichever happens to be negative relative to the other at any given in-

stant. Here again the action distinguishes fundamentally from that due to an instantaneous removal of the force impelling the electron stream, as by capacitively short circuiting the line with condenser C_2 .

In the case of the alternating current supply, the relay may of course be released in the same fashion as was described with reference to direct current. An isolated connection of condenser C_2 to the line will cause the relay to release and reoperate, whereas intermittent connection of the condenser by rotation of switch S , will maintain the relay in its released condition.

The action occurring here is easily understood if switch S is rotated synchronously with the applied alternating current voltage in such phase relation as to bridge condenser C_2 across the line during a portion of each cycle that the current is building up in the space path of the tube. This will have the effect of practically eliminating the normal pulses of space current, so that the average current flowing through the tube will be practically nil. Synchronous rotation of the switch in this manner is quite simply effected by mounting the rotary switch contacts upon the shaft of a synchronous motor, such as is employed in electric clocks.

It has been found in practice that it is not necessary to relate rotation of the switch to the phase of the applied potential in the manner stated. Random bridging of the condenser will suffice provided the speed of rotation is sufficiently high.

In view of the foregoing explanation it will now be understood how the conductors of the residence lighting system may be utilized simultaneously for remote signaling control and power supply purposes, mutually independent of one another. The control system requires for its operation an instantaneous reduction in line voltage to an excessively low value, in order to establish the effects upon which action of the system depends. In normal operation of the line for power supply purposes, the line voltage seldom changes more than a few volts, insufficient to affect the relay circuit. In general the power load is resistive and inductive rather than capacitive, hence no action is obtained from the power load analogous to connection of condenser C_2 . On the other hand the large charging current taken by condenser C_2 is of such short duration, and of such small total energy content, as to produce no observable effects upon the power line equipment.

In order to enable those skilled in the art to practice the invention, the following electrical values and apparatus have been found to produce satisfactory operation as applied to the usual residence lighting and power supply systems:

Condenser C_2 =1 to 3 microfarads
Condenser C_1 =1 microfarad

Relay R =Western Electric Co. alternating current telephone relay, A-8.

Tube V =National Union 12-A

The modification of Fig. 2 differs from that of Fig. 1 principally in that the control grid G is connected to both sides of the line 3 through identical impedances, each comprising a condenser C_3 in series with a resistance R_3 . With this arrangement the control grid G is normally maintained at a positive potential relative to its cathode equal to one-half the line voltage. Upon bridging the actuating capacity C_2 across the line, condensers C_3 commence to discharge through the relatively high resistances R_3 , of

the order of 100,000 ohms each. This causes the grid potential to be reduced instantaneously to zero relative to the cathode. The resultant decrease in space current is sufficient to release relay R .

It has been found that the values of the various resistances and capacities need not be particularly precise, but a balance between all units involved is preferable. That is, the resultant capacity of the condensers C_3 in series should be approximately equal to the capacity of the actuating condenser C_2 . Condenser C_1 bridging the winding of relay R is not required with this circuit. Performance is improved by its addition, however.

An analogy in operation between the Fig. 1 and the Fig. 2 circuits is to be found in the negative potential applied to the control grid in each instance. Whereas in the Fig. 1 modification the negative grid potential is accumulated from the electronic stream, in the Fig. 2 modification it is positively applied from the line.

Capacity C_1 need not comprise a distinct condenser unit, but may in fact constitute the distributed capacity of the winding of actuating element R suitably wound to this end.

In the circuit of Fig. 3 the control apparatus is employed for protection purposes on a power line. Conductors 30 extend to generator E to be protected, while conductors 31 extend to a power transmission line exposed to short circuits, lightning, etc. Conductors 30 normally extend through contacts 32 and 33 of a plunger type relay or circuit breaker R to conductors 31. The relay is normally energized, in the manner described, by the space current of tube V supplied from source E .

If now a transient of short circuit magnitude originates along lines 31, the resultant interruption of space current in tube V will momentarily deenergize relay R in the manner described, whereupon spring 34 will withdraw plunger 35 until resilient pin 36 engages lug 37 to lock the plunger in its released condition. The release of plunger 35 opens the line at contacts 32 and 33. After the line trouble is cleared the circuit breaker is reset manually in the usual manner.

In the case of high tension lines, the control apparatus may be located in an auxiliary low voltage circuit, coupled inductively or capacitively to the high tension lines, as by paralleling the high tension system with a short section of the auxiliary circuit. Operation of the control apparatus would of course be then arranged to open the high tension lines.

I claim:

1. Control apparatus comprising a space discharge device including an anode and a cathode connected respectively to opposite conductors of an electrical power supply line, said tube having a control grid connected through high impedance to at least one said conductor and actuating means interposed in said anode connection responsive to interruptions in the space current of said device.

2. Control apparatus comprising a space discharge device having an anode and a cathode connected respectively to opposite conductors of an electrical power supply line, means energizing said cathode, and an actuating element shunted by capacity interposed in said anode connection, said apparatus responding to transient electrical disturbances of short circuit magnitude affecting said power line.

3. Control apparatus comprising a space dis-

charge device having an anode and a cathode connected respectively to opposite conductors of an electrical power supply line, and a grid connected to at least one said conductor through high impedance, means energizing said cathode, and a relay shunted by capacity interposed in the anode connection of said device, said apparatus responding to transient electrical disturbances of short circuit magnitude affecting 10 said power line.

4. Control apparatus comprising a space discharge device having a cathode connected to at least one conductor of an electrical power supply line, an anode connected with an opposite conductor thereof, and an interposed grid maintained free of electrical connection, means energizing said cathode, and actuating means interposed in said anode connection responsive to interruptions in the space current of said device. 15
5. In combination, an electronic tube having a control grid connected through impedance with opposite conductors of an electrical power supply line, and a cathode connected with at least one said conductor, whereby the space current of 20 said tube responds to potential variations of said line. 25
6. In combination, an electronic tube having a control grid connected through series resistance and capacity with opposite conductors of an electrical power supply line, a cathode connected with at least one said conductor, whereby the space current of said tube responds to potential variations of said line, and an anode having in circuit therewith an actuating element responsive 30 to interruptions of said space current variations. 35

7. In combination, an electronic tube having a control grid connected through series resistance and capacity with opposite conductors of an electrical power supply line, a cathode connected with at least one said conductor, whereby the space current of said tube responds to potential variations of said line, an anode having in circuit therewith an actuating element responsive to said space current variations, and means including a condenser for capacitively short circuiting said line to actuate said element. 40
45

8. In combination, an electronic tube having a cathode and an anode connected respectively with opposite conductors of an electrical power supply line, and a control grid connected to impedance, the latter connected between said conductors whereby the space current of said tube responds to potential variations of said line. 50

9. In combination, an electronic tube having a cathode and an anode connected respectively with opposite conductors of an electrical power supply line, and a control grid connected to impedance, the latter connected between said conductors whereby the space current of said tube responds to potential variations of said line, and actuating means interposed in said anode connection responsive to said space current variations. 55
60

10. Electrical control apparatus comprising a space discharge device including an anode and a cathode, means energizing said device, actuating means responsive to the flow of space current in said device, and means including a condenser for momentarily short circuiting said energizing means thereby to interrupt said space current and effect response in said actuating means. 65
70

11. Electrical control apparatus comprising a space discharge device having an anode and a cathode, a potential source for energizing said 75

device, actuating means responsive to the flow of space current in said device, and means including a condenser for capacitively short circuiting said potential source to effect response in said actuating means. 5

12. Electrical control apparatus comprising a space discharge device having an anode, a cathode and an interposed control electrode, a potential source for energizing said device, actuating means responsive to the flow of space current in said device, and means including a condenser for capacitively short circuiting said potential source to effect response in said actuating means. 10

13. Electrical control apparatus comprising a space discharge device having an anode, a cathode, and an interposed control grid, a potential source for energizing said device, an actuating element shunted by capacity responsive to the flow of space current in said device, and means including a condenser for capacitively short circuiting said potential source to effect response of said element. 15
20

14. A remote control system operable from an electrical power supply line comprising, a space discharge device having a cathode and an anode connected respectively with opposite conductors of said line, means energizing said cathode, actuating means included in said anode connection responsive to interruptions in the flow of space current in said device, and means for capacitively short circuiting said line at a remote point to effect response in said actuating means. 25

15. Remote control apparatus operable from an electrical power supply line comprising, a space discharge device having an anode and a cathode connected respectively with opposite conductors of said line, and an interposed grid, means energizing said cathode, actuating means interposed in said anode connection responsive to interruptions in the space current of said device, and means for capacitively short circuiting said line at a remote point to effect response in said actuating means. 30
35

16. Remote control apparatus operable from a power supply line comprising, an electronic tube having an anode and a cathode connected respectively with opposite conductors of said line, and an interposed grid maintained free of electrical connection, means energizing said cathode, an actuating element shunted by capacity interposed in said anode connection, and means including a condenser for short circuiting said line at a remote point to effect response of said element. 40

17. Remote control apparatus operable from a power supply line comprising, a space discharge device having a control grid connected through series resistance and capacity, with each conductor of said line, a cathode connected with at least one said conductor, and an energized anode having in circuit therewith actuating means responsive to interruptions in the space current of said device, and means for capacitively short circuiting said line at a remote point to effect response in said actuating means. 60

18. Remote control apparatus operable from an electrical power supply line comprising, an electronic tube having an anode and a cathode connected respectively with opposite conductors of said line, and an interposed control grid, a normally actuated element shunted by capacity interposed in said anode connection, and means at a remote point for capacitively short circuit- 70

ing said line intermittently at a rate effecting continuous deenergization of said element.

19. Protective control apparatus for an electrical power supply line comprising, an electronic tube having an anode and a cathode connected respectively with opposite conductors of said line, and circuit breaking means shunted by capacity included in said anode connection responsive to interruptions in the space current of 10 said tube to open said line.

20. The method of utilizing an electrical power supply line while operating in its normal manner for remote control operation which comprises, establishing a localized flow of space discharge current between the conductors thereof

in response to the line voltage, interrupting said space discharge current in accordance with control impulses by capacitively short circuiting said line, and utilizing said space current interruption for remote control actuation.

21. The method of utilizing transient electrical disturbances on a power line for control actuation which comprises, establishing a localized flow of space discharge current between the conductors thereof in response to the line voltage, 10 causing said transient effects to interrupt the said flow of space current, and utilizing said current interrupting for purposes of control actuation.
